UNITED STATES PATENT OFFICE

146,920

DESIGN FOR A LIGHTER OR SIMILAR
ARTICLE

Frederick Kaupmann, Brooklyn, N. Y., assignor to
Ronson Art Metal Works, Inc., Newark, N. J.,
a corporation of New Jersey

Application December 6, 1945, Serial No. 124,433

Term of patent 14 years

(Cl. D48—27)

To all whom it may concern:

Be it known that I, Frederick Kaupmann, a citizen of the United States, residing at Brooklyn, in the county of Kings and State of New York, have invented a new, original, and ornamental Design for Lighter or Similar Article, of which the following is a specification, reference being had to the accompanying drawing, forming part thereof.

Figs. 1 and 2, respectively are front and rear elevational views of the lighter showing my design;

Figs. 3 and 4, respectively are side elevational views of the lighter shown in Figs. 1 and 2;

Fig. 5 is a top plan view of the lighter shown in Figs. 1 and 2;

Fig. 6 is a bottom plan view of the lighter shown in Figs. 1 and 2;

Fig. 7 is a perspective view showing the lighter in operated condition; and

Fig. 8 is a front elevational view showing the lighter in operated condition.

I claim:

The ornamental design for a lighter or similar article, substantially as shown.

FREDERICK KAUPMANN.
